US0D1008452S

(12) **United States Design Patent** (10) **Patent No.:** **US D1,008,452 S**
(45) **Date of Patent:** **** Dec. 19, 2023**

(54) **LOCK MEMBER**

(71) Applicant: **DEKA Products Limited Partnership**,
Manchester, NH (US)

(72) Inventor: **Richard J. Lanigan**, Concord, NH
(US)

(73) Assignee: **DEKA Products Limited Partnership**,
Manchester, NH (US)

(**) Term: **15 Years**

(21) Appl. No.: **29/805,349**

(22) Filed: **Aug. 26, 2021**

(51) **LOC (14) Cl.** **24-02**

(52) **U.S. Cl.**

USPC **D24/127**

(58) **Field of Classification Search**

USPC D24/127-130, 227-228, 231, 232, 206;
D8/394, 339, 342, 343, 382, 330, 331,
D8/338, 341, 347

CPC Y10T 403/4602; Y10T 403/553; Y10T
403/75; Y10T 403/472
